COMBINED TYPE-WRITING AND COMPUTING MACHINE.

1,144,975.

Specification of Letters Patent. Patented June 29, 1915.

Application filed August 19, 1913. Serial No. 785,454.

To all whom it may concern:

Be it known that I, LESTER A. WERNERY, a citizen of the United States, residing in Brooklyn borough, city of New York, in the county of Kings and State of New York, have invented certain new and useful Improvements in Combined Type-Writing and Computing Machines, of which the following is a specification.

10 My invention relates to an improved means to prevent the type-bars of a combined typewriting and computing machine from printing during computation.

An object of the invention is to provide 15 a device of this character which shall be of simple construction and inexpensive, and at the same time efficient and reliable in operation, which may also be very quickly attached to or removed from the machine, 20 or shifted into or out of operative position without removal from the machine, and which moreover requires little or no alteration of the standard forms of machines.

A stop in the form of a horizontally-disposed rod located adjacent the printing 25 point, is shiftable vertically into and out of position substantially over the printing point, so that when in effective position it can serve as a stop for the types, and prevent them from printing. When the type-bars are provided with upper and lower 30 case types, said stop preferably engages the type-bar between the two types, allowing the type-bar to substantially complete its stroke.

35 The ends of the stop rod are vertically disposed and adjustably supported in upright guiding members removably mounted on the type bar segment. Said guiding members carry spring detents to engage 40 notches in the stop rod to hold it in adjusted position.

The present invention is a modification of that disclosed in the application of W. L. Dench, Serial No. 784,213, filed August 45 11, 1913, and is limited to features not disclosed in said application.

Other features and advantages will hereinafter appear.

In the accompanying drawings which 50 illustrate the invention as applied to an Underwood-Hanson combined typewriting and adding machine, Figure 1 is a perspective view of the stop device and associated parts of the machine to which it is applied. 55 Fig. 2 is a sectional side elevation view. Fig. 3 is a front elevation view of the stop

and its supports. Fig. 4 is a perspective view of the stop. Fig. 5 is a similar view of one of the supports.

The type-keys 1 are mounted on levers 2 connected through bell cranks 3 to swing the type-bars 4, pivoted in the slotted segment 5, upwardly and rearwardly against the platen 6, on which the work-sheet is supported. As the type-bars approach the printing point they enter the usual type guide 7 mounted on the segment 5 and secured in position by screws 8. The numeral keys in the form of machine herein shown are provided with pendants 9 to strike bell 10, so as to set up on computing mechanism (not shown) the numbers represented by the numeral keys struck. If it is desired to set up numbers without printing them on the platen, a stop 11 is moved into position to intercept the type-bars before they reach the printing point.

The stop is preferably formed from a wire rod having a horizontal stop portion and depending members 12 supported and vertically adjustable in guiding supports 13, mounted on the segment 5. The supports 13 comprise vertical side plates 14 spaced to receive the members 12 of the stop. On each support 13 is secured a leaf spring 15 having its upper end 16 rolled to form a spring detent engageable in notches or depressions 17 and 18 in the stop 11 to hold the latter respectively in operative and inoperative positions. Pins 19 connecting the side plates of the supports 13 prevent displacement of the stop 11 in a forward direction.

The lower ends of the stop rod 11 have horizontal forward projections 20 adapted to engage the lower pins 19 and thereby form a positive means to prevent accidental removal of the stop from its supports. Horizontal sections 21 of the members 12 offset the stop 11 rearwardly to bring it in close proximity to the platen. The supports 13 may be removably attached to the segment 5 by means of dowel pins 22 adapted to enter suitable openings in the segment, and so positioned that the flat sides 105 of the supports will bear against the sides of the type guide 7 and thus hold the supports 13 against rotation. This construction permits the stop 11 and its guiding supports 13 to be instantaneously attached 110 to or removed from the machine. Also in the type of machine shown no alteration of

the machine is required to adapt it for the attachment, as such machines are provided with holes drilled in the segment 5 for the attachment of card holders and the like, 5 which holes serve for the dowel 22 in the present invention.

It will be noted that when the stop 11 is in its lowered or operative position, as shown in Fig. 2, it extends directly between the 10 upper and lower case types and the actuated type-bar. The type-bar is thus permitted to substantially complete its stroke while at the same time the type is positively prevented from coming in contact with the platen. 15 With the present arrangement the touch is practically unchanged by the use of the stop 11, and the types are permitted to strike the universal bar 23 and operate the escapement mechanism controlled thereby in the 20 usual manner.

While the stop 11 is in use, the spring detents 16 engage the notches 17 and hold the stop in operative position. When it is desired to discontinue the use of the stop, it is 25 simply pulled upwardly until the detents 16 snap into the lower notches 18.

The entire device may at any time be removed by simply lifting the supports 13, together with the stop 11 as a unit, from the 30 machine.

Variations may be resorted to within the scope of the invention, and portions of the improvements may be used without others.

Having thus described my invention, I 35 claim:

1. In a combined typewriting and computing machine, the combination with a rotatable platen, of a type-bar having upper and lower case types therein, and a stop in 40 position to engage the type-bar between said types during the printing stroke and thereby prevent printing.

2. In a combined typewriting and computing machine, the combination with a rotatable platen and type-bars, of a stop rod 45 extending in the direction of the platen axis and bodily movable in a direction transverse to the platen axis into and out of position to intercept the type-bars.

3. In a combined typewriting and computing machine, the combination with a horizontally-disposed rotatable platen and type-bars adapted to swing upwardly and forwardly to strike the front face of the 55 platen, of a horizontal stop rod extending along the face of the platen adjacent to the printing point, and guides in which said rod is vertically movable into and out of position to stop the type-bars as they approach the printing point.

4. In a combined typewriting and computing machine, the combination with a rotatable platen and type-bars to strike the

platen, of a horizontal stop rod extending on opposite sides of the printing point, depending guiding members on said rod, and supports in which said members are supported and vertically adjustable to bring said stop into and out of position to stop the type-bars. 65

5. In a combined typewriting and computing machine, the combination with a rotatable platen and type-bars to strike the platen, of a stop rod extending across the path of the type-bars and on opposite sides 75 of the printing point, depending guiding members on said rod, and stationary supports in which said members are supported and vertically adjustable into and out of the path of the type-bars to bring said stop into 80 and out of position to stop the type bars.

6. In a machine of the character described, the combination with a typewriter platen and type-bars, of a stop rod movable 85 into and out of position to stop the type-bars, and supports in which the stop is adjustably mounted.

7. In a machine of the character described, the combination with a platen, a type-bar segment and type-bars, of a stop, 90 and supporting and guiding members for said stop removably mounted on the segment.

8. In a machine of the character described, the combination of a type-bar segment, a stop rod, and supporting and guiding members for the stop rod, said members having dowel pins to enter openings in the 95 segment and thereby removably support said members on the segment.

9. In a machine of the character described, the combination of a type-bar segment, a stop rod, supporting and guiding members for the stop rod, said members having dowel pins to enter openings in the 105 segment and thereby removably support said members on the segment, and a type guide mounted on the segment and bearing against said members, thereby preventing rotary movement of the said members. 110

10. In a machine of the character described, the combination with a type-bar segment, of a type-bar stop, and supports for said stop on the segment and liftable out of contact therewith. 115

11. In a machine of the character described, the combination with a type-bar segment, of a type-bar stop extending horizontally across the printing point, and supports mounted on the segment in which said stop is vertically adjustable into and out of 120 operative position.
